(57) **CLAIM**

The ornamental design for a table, as shown and described.

DESCRIPTION

FIG. 1 is a perspective view of a table showing my new design;

FIG. 2 is a front elevational view of the table, the rear side, left side, and right side of which are identical;

FIG. 3 is a top plan view of the table; and,

FIG. 4 is a bottom plan view of the table.

The broken lines in the drawings are included to show portions of the table that form no part of the claimed design.
